[57] CLAIM

The ornamental design for an ornamental public information access terminal or similar article, substantially as shown and described.

DESCRIPTION

FIG. 1 is an isometric view of an ornamental public information access terminal or similar article showing my new design;

FIG. 2 is a front elevation view thereof;

FIG. 3 is a left side elevation view thereof;

FIG. 4 is a right side elevation view thereof; and,

FIG. 5 is back elevation view thereof.

FIG. 1

FIG. 2

FIG. 3

FIG. 4

FIG. 5

UNITED STATES PATENT AND TRADEMARK OFFICE
CERTIFICATE OF CORRECTION

PATENT NO. : Des. 339,329

DATED : September 14, 1993

INVENTOR(S) : Mark Lacko and John Laverac

It is certified that error appears in the above-identified patent and that said Letters Patent is hereby corrected as shown below:

On the title page, under item [19], change "Lacko" to --Lacko et al.--; item [75], after "N.Y." insert --; John Laverac, Garrison, N.Y. --; item [57], lines 1-2, change "an ornamental public information access" to --a public access information-- and delete "or similar article substantially".

Description, Lines 1-2, change "an isometric" to --a perspective --and change "an ornamental public information access" to --a public access information--; line 2, delete "or similar article"; line 3, change "my" to --our--; line 4, change "elevation" to --elevational--; line 5, change "elevation" to --elevational--; line 6, change "elevation" to --elevational--; and line 7, change "elevation" to --elevational--.

On the title page, item [54], should read --PUBLIC ACCESS INFORMATION TERMINAL--.

Signed and Sealed this

Thirtieth Day of August, 1994

Attest:
